ENGINE STARTER

Frank H. Prescott, Anderson, Ind., assignor, by
mesne assignments, to General Motors Corporation,
Detroit, Mich., a corporation of Delaware

Application May 29, 1931, Serial No. 540,845
Renewed August 31, 1934

8 Claims. (CL. 290—37)

This invention relates to electrical apparatus for starting an internal combustion engine for propelling an automotive vehicle.

It is one of the objects of the present invention to control the engine starting apparatus in response to the control of other electrical apparatus associated with the engine such as the ignition apparatus, for example, and also to control the engine starter in response to the operation of some mechanical device associated with the engine which device might be operated to advantage to facilitate the starting of the engine. One such device is the clutch pedal which may be depressed to disconnect the engine from the transmission thus releasing the starting motor from driving any more than is necessary during engine cranking. The present invention embraces the use of either the ignition switch or the clutch pedal or both to control the engine starter. In conjunction with these controls it is the principal purpose of the present invention to provide means for preventing the use of the engine starter while the engine is running on its own power. This purpose is accomplished by providing electro-magnetic means associated with the storage battery and battery charging generator driven by the engine in such manner that the electro-magnetic means is rendered effective on current from the battery alone to cause the starting motor to be connected with the engine and to crank the engine, said electro-magnetic means being non-operative while the generator is being driven by the engine at an appreciable rate of speed.

As a further safeguard against operation of the starting apparatus while the engine is running the present invention provides means responsive to engine suction for locking the engine starting apparatus against operation, this means being effective to prevent operation of the starter so long as the engine is running, even if the generator for any reason becomes inoperative.

Further objects and advantages of the present invention will be apparent from the following description, reference being had to the accompanying drawing wherein a preferred embodiment of one form of the present invention is clearly shown.

In the drawing:

Fig. 1 is a wiring diagram illustrating a form of the present invention.

Fig. 2 is a fragmentary showing of a modification thereof.

In the diagram the engine is represented by a fly-wheel gear 20 adapted to be engaged by a pin-

ion 21 connected by a one-way roller clutch 22 with a longitudinally splined shaft 23 driven by an electric motor 24 having a ground connection 25 and connected with a switch contact 26. Contact 26 is connected with a contact 28 by a movable contact 27 actuated by a button 29 which is operated by means later described against the action of a compression spring 30. The contact 28 is connected by a wire 31 with a storage battery 32 grounded at 33. A generator 40 driven by the engine is grounded at 41 and is connected by a wire 42 with a cut-out or reversely ground relay 43 which in turn is connected by a wire 44 with wire 31.

The ignition apparatus of the engine is not shown but it will be understood that it is connected with the generator 40 or battery 31 by switch 50 also connected by wire 51 with a switch contact 52 adapted to be connected by the movable contact 53 with a switch contact 54. The contact 53 is actuated against a compression spring 55 by a switch button 56 located in the path of movement of a lug 57 projecting from the automotive clutch pedal 58 which is pivoted at 59 in the usual manner. The contact 54 is connected by a wire 60 with a magnet winding 61 connected by wire 62 with wire 42 at a point between the generator 40 and cut-out relay 43. The magnetic winding 61 operates with a magnetizable armature 63 carried by preferably a magnetizable bar 64 which passes through the coil 61. The left end of bar 64 carries a pin 65 received by a notch 66 in the upper end of a lever 67 pivoted at 68 and carrying on its lower end a stud 69 received by a groove 70 in the one-way clutch 22. A spring 71 yieldably urges the lever 67 against a stop 72, in which position of the lever, the pinion 21 is maintained out of engagement with the gear 20. The lever 67, not only effects engagement of the pinion 21 with gear 20 but is located so as to operate the switch button 28, when the lever is rocked in a clockwise direction by the operation of the magnet which is controlled in a manner more specifically described hereinafter.

The right end of the bar 64 is provided with a notch 88 adapted to receive a plunger or rod 81 slidable through a bearing 82 provided in the lower part of a cup-shaped housing closed at its upper end by a flexible diaphragm 84, the periphery of which is clamped on the flange 85 at the top of the cup 83, by a cover 86 having a vent 87, to admit atmospheric pressure to the top of the diaphragm. A spring 88 bearing against the bottom wall of the cup 83 and 55

against a head 90 of the rod 81 urges the diaphragm 84 upwardly and locates the rod 81 so that its lower end is above and clear of the notch 80. The space within the cup 83 and below the diaphragm 84 provides a suction chamber connected by pipe 91 with the intake manifold 92 of the engine.

The operation of the present invention is as follows: the operator first closes the ignition switch 50 to connect the ignition apparatus with the storage battery 32. He then depresses the clutch pedal 58 and the lug 57 is caused to engage the button 56 thereby moving contact 53 into engagement with contacts 52 and 54. When this occurs the magnetic coil 61 will be energized and will attract the armature 63 toward the right, moving lever 67 clockwise, and the clutch 22 and pinion 21 toward the left along the splined shaft 23. During the meshing of the pinion 21 with the fly wheel gear 20 the lever 61 engages the switch button 29 and is therefore effective to move the contact 27 into engagement with contacts 26 and 28 when the pinion 21 and gear 20 are properly engaged thereby connecting the starting motor 24 with the battery 32. The motor 24 will, therefore, operate to crank the engine through the mechanical connections provided between the splined shaft 23 and the clutch 22, between the clutch 22 and the pinion 21, and between the pinion 21 and the fly wheel gear 20.

When the engine becomes self-operative the suction in the intake manifold will be sufficient to cause the rod 81 to move downwardly against the spring 89 until the rod engages the upper surface of the bar 64. As the generator speed increases and its voltage therefore increases, the voltage impressed by the generator 40 upon the coil 61 will oppose the voltage impressed by the battery 32 upon the coil 61 thereby weakening the E. M. F. of the coil 61 to such an extent that the spring 71 becomes effective to move the lever 67 counterclockwise and the rod 64 toward the left thereby demeshing the pinion 21 from the engine gear 20 and thereby moving the bar 64 into such position that the starting apparatus cannot be operated through the agency of the magnet 61. As the lever 67 is moved counterclockwise in the manner described the rod 81 is snapped into the notch 80 in the bar 64 by the action of engine suction, and thus locks the bar against movement as long as the engine is running. This lock is effective to prevent reoperating of the starting mechanism during engine operation even if the generator should fail in the function of maintaining the magnet coil 61 ineffective during engine operation.

Also the operator will normally release the clutch pedal 58 as soon as the engine fires but should he fail to do so the demeshing of the pinion 21 from the engine gear 20 will take place in the manner described. Failure to release the clutch pedal promptly after starting the engine can do no harm except to decrease slightly the amount of current flowing from the generator to the storage battery and ignition apparatus. By making the coil 61 of a relatively large number of turns of fine wire the coil resistance will be made sufficient to cause the amount of current flowing from the generator to be relatively small. Under these conditions the clutch pedal control of the coil 61 might be eliminated, the wire 61 being connected directly with the wire 60 by a wire 51A indicated by dot and dash lines in the diagram.

In this case the starting apparatus would be controlled solely by the ignition switch.

Instead of applying the clutch pedal control of the engine starting apparatus to a switch in series with the controlling magnet 61 the clutch pedal might be used to control the switch located in series with the starting motor switch provided with contacts 26, 27 and 28. More specifically a circuit wire 31 could be interrupted between points A and B and these points could be connected by a switch operated by the clutch pedal. As shown in Fig. 2 points A and B are connected with contacts 93 and 94 respectively, adapted to be bridged by a movable contact 95 carrying a button 96 located in the path of movement of the lug 57 of the clutch pedal 58 and actuated thereby against the action of the compression spring 97. When the clutch pedal operated switch is employed the clutch circuit of the magnet 61 is omitted, wires 51 and 60 being jointed by wire 51A.

While the form of embodiment of the present invention as herein disclosed, constitutes a preferred form, it is to be understood that other forms might be adopted, all coming within the scope of the claims which follow.

What is claimed is as follows:

1. Engine starting apparatus for automotive vehicles, comprising in combination, a current source, a starting motor, a switch for effecting the connection of the current source and the motor, automatic means for controlling the operation of said switch, said means including a generator, and an electromagnet having a coil subject to the difference between the voltages of said source and said generator, and a positive lock for preventing actuation of the automatic means during operation of the engine.

2. Engine starting apparatus for automotive vehicles, comprising in combination, a current source, a starting motor, a switch for effecting the connection of the current source and the motor, automatic means for controlling the operation of said switch, said means including a generator, and an electromagnet having a coil subject to the difference between the voltages of said source and said generator, and a second switch for rendering said first mentioned switch effective, said second switch being constructed and arranged to be operated by the vehicle clutch pedal, and a lock for holding the electromagnet in switch open position during operation of the engine independently of the generator.

3. Engine starting apparatus for automotive vehicles, comprising in combination, a current source, a starting motor, a switch for effecting the connection of the current source and the motor, automatic means for controlling the operation of said switch, said means including a generator, and an electromagnet having a coil subject to the difference between the voltages of said source and said generator, a second switch for controlling operation of said first mentioned switch, said second switch being constructed and arranged to be operated by the vehicle clutch pedal, and suction operated means preventing operation of said first named switch on operation of the clutch pedal while the engine is running.

4. Engine starting apparatus for automotive vehicles comprising, in combination, a current source, a starting motor, a switch for effecting the connection of the current source with said motor, automatic means for controlling the operation of said switch, said means including a generator, an electromagnet controlled by the

generator and adapted to open and close the switch and a positive lock for preventing any operation of the electromagnet when the engine is running under its own power, irrespective of the 5 action of the generator.

5. Engine starting apparatus for automotive vehicles comprising, in combination, a current source, a starting motor, a switch for effecting the connection of the current source with said 10 motor, automatic means for controlling the operation of said switch, said means including a generator, an electromagnet controlled by the generator and adapted to open the switch of the starting motor when the generator is charging at 15 a predetermined rate, and means for positively locking the electromagnet in switch open position after it has been so moved by action of the generator and maintaining it locked in this position as long as the engine continues to run under its own power irrespective of the action of the generator.

6. Engine starting apparatus for automotive vehicles comprising, in combination, a current source, a starting motor, a switch for effecting 20 the connection of the current source with said motor, automatic means for controlling the operation of said switch, said means including a generator, an electromagnet controlled by the generator and adapted to open the switch of the 25 starting motor when the generator is charging at a predetermined rate and means operated by 30

engine suction for positively locking the electromagnet in switch open position after it has been so moved by action of the generator and maintaining it locked in this position as long as the engine continues to run under its own power irrespective of the action of the generator. 5

7. Engine starting apparatus for automotive vehicles, comprising in combination, a current source, a starting motor, a circuit between the starting motor and the current source, a switch 10 for closing said circuit, a generator, automatic means for operating said switch including an electromagnet having a coil subject to the difference between the voltages of said current source and generator, and means operable by the 15 engine for preventing operation of said magnet during operation of the engine.

8. Engine starting apparatus for internal combustion engines of automotive vehicles, comprising in combination, a current source, a starting motor, 20 a circuit between the starting motor and the current source, a switch for controlling said circuit, a generator, automatic means for operating said switch including an electro-magnet having a coil subject to the difference between the voltages of 25 the current source and the generator, an ignition switch and a switch operable by the vehicle clutch pedal for controlling the operation of said magnet and means operable by the engine for preventing operation of the magnet during engine operation. 30
